UNITED STATES PATENT OFFICE.

URIAH C. MILLER, OF WAURIKA, OKLAHOMA.

KNEE-PAD.

1,317,305.

Specification of Letters Patent. Patented Sept. 30, 1919.

Application filed June 25, 1918. Serial No. 241,801.

To all whom it may concern:

Be it known that I, URIAH C. MILLER, a citizen of the United States, residing at Waurika, in the county of Jefferson and 5 State of Oklahoma, have invented a new and useful Knee-Pad, of which the following is a specification.

The subject of this invention is a knee-pad intended for use by the agriculturalist, 10 though the same may be used to advantage by those engaged in other occupations.

The main object of the invention is the provision of a knee-pad which will support and protect the knee of one whose occupation requires that he go upon his knees in order to perform his labors, such as the cotton picker, berry picker, and those engaged in many other lines of endeavor.

Another object of the invention is the 20 provision of a pneumatic pad.

Another object of the invention is the provision of a reinforced pad.

The invention also contemplates generally improving the construction and enhancing the utility of knee-pads.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:—

Figure 1 is a front end elevation of a 40 knee-pad constructed in accordance with the invention;

Fig. 2 is a side elevation of the same;

Fig. 3 is a transverse section of the device;

Fig. 4 is a vertical longitudinal section. Referring to the drawing by numerals of reference:—

In carrying out the invention there is provided a substantially semi-cylindrical

member 1, formed of continuous, spaced 50 inner and outer walls, as seen most clearly in Figs. 3 and 4. A plaited filler 2 is placed between the inner and outer walls to which it is connected by stitching or otherwise, and the plaits of this filler extend longitudinally of the device. Any suitable material may be used for the member 1 and the 55 filler 2, but the same are preferably made of cloth, and the cloth forming the walls of the member 1 is rubberized or otherwise rendered air tight.

An ordinary valve 3 is provided and is in communication with the interior of the member 1 to permit air to be forced into the member so as to inflate the same. This may 60 be done by means of the ordinary small hand pump, not shown, or in any other manner.

A sheet of rubber 1', or the like, is secured 70 to the under surface of the member 1 and serves to protect and reinforce the same, and a portion of the sheet is turned up to form a head for the forward end of the semi-cylindrical member, as seen most clearly in 75 Figs. 1, 2 and 4. The provision of a head or closure at the forward end of the member 1 serves to retain the member in suitable position with respect to the knee of the user and prevents the pad from sliding back as the user moves forward upon his knees. 80

Straps 4 are secured to the member 1 in any suitable manner, and these straps may be reinforced by the retaining straps 5. The straps 4 are adapted to be engaged and held by buckles 6 which are secured to the 85 opposite edge of the member 1 by means of the retaining straps 7, which are secured by rubber, glue or otherwise, to the member. These straps are buckled about the calf of the leg of the user of the pads and retain 90 the pads in position.

It will be seen that these pads not only protect the knees from wear due to the rough surfaces over which one is compelled to move, but also act as a cushion for the 95 knee, and support it in comparative ease and comfort.

Having thus described the invention,

what is claimed as new and sought by Letters Patent, is:—

A knee pad, consisting of an inflatable member, means for securing said member, and a filler in said member composed of longitudinal plaits whose edges rest against the inner walls of the said member.

In testimony that I claim the foregoing as my own I have hereto affixed my signature in the presence of two witnesses.

URIAH C. MILLER.

Witnesses:

JAMES H. WEBB,
BURTON L. DOGGETT.
